METHOD AND APPARATUS FOR MAKING
COMPOSITE GLASSJames H. Sherts, Brackenridge, Pa., assignor to
Duplate Corporation, a corporation of Dela-
ware

Application April 16, 1930. Serial No. 444,684

4 Claims. (Cl. 18—17)

The invention relates to apparatus for making composite glass, and constitutes an improvement on the apparatus shown and described in my application, Serial No. 403,510. The apparatus comprises a metal platen heated by means of a fluid, such as steam, or a hot liquid, such as carbitol, on which the sheets to be composited are supported, and a cover provided with a rubber diaphragm on its lower side which fits over the platen with air pressure means leading to the space behind the diaphragm, in order to composite the sheets. In this apparatus, all the heat necessary for compositing is supplied from beneath the sheets by the heated platen, and the pressure is applied above the diaphragm. Preliminary to the pressing operation, air is exhausted from the space beneath the diaphragm in order to withdraw any air which may be entrapped between the sheets. The present improvement is designed to increase the life of the rubber diaphragms, which have been found to cut out rapidly in service and to provide for a more complete withdrawal of the air from between the sheets to be composited preliminary to the pressing operation. Briefly stated, the invention consists in the use of a relatively thin rubber sheet which is placed over the sheets to be composited preliminary to the step of exhausting the air from between the sheets and preliminary to applying the compositing pressure. The use of this additional sheet protects the diaphragm from cutting and wearing where it engages the corners of the upper glass sheet of the series, and thus increases the life of such diaphragm several times over. For the reason later explained, its use also permits of a much more complete exhaustion of the air from between the sheets, so that air pockets in the composited plates are avoided and the quality of the product improved. One embodiment of the invention is shown in the accompanying drawing, wherein:

Figure 1 is a vertical section through the apparatus in open position. And Fig. 2 is a similar view on an enlarged scale but with the lid of the apparatus closed.

Referring to the drawing, 1 is the platen of a press similar to that shown in my application heretofore referred to. This platen constitutes the upper wall of the chamber 2 for the fluid which heats the platen. The fluid is applied through the connections 3, 4 and 5 and may be steam or a liquid heated to a temperature sufficient for the purpose. The upper surface of the platen is provided with a series of grooves 6 all connected with the pipe 7 by means of which the air may be

exhausted from the space above the platen preliminary to the application of compositing pressure, as hereinafter described. The platen 1 is mounted in a suitable hollow framework 8 closed on the lower side by the plate 9. The cover of the device comprises a plate 10 hinged to one of the members 8, as indicated at 11, and provided with a latch bar 12 by means of which the lid may be locked in closed position, at which time the bar 12 may be moved beneath the lugs 13 carried by the member 8. Secured to the lower side of the lid is the rubber diaphragm 14, the edges of such diaphragm lying between the clamping strips 15 secured in position by means of the screws 16. Air is supplied to the space 17 behind the diaphragm by means of the pipe 18 connected to a suitable source of supply. As indicated in Fig. 2, the set of sheets to be composited comprises a pair of glass sheets 19, 19 and an interposed sheet 20 of pyroxylin plastic, the opposing surfaces of the sheets being provided with a suitable cement for sticking them together upon the application of heat and pressure as is well known in the art. Interposed between the bottom sheet of glass 19 and the platen 1 is a sheet of woven metal screen 21, preferably copper, such sheet being somewhat greater in area than that of the sheets to be composited. The use of this sheet 21 constitutes a departure from my application heretofore referred to and constitutes no part of my invention. This sheet of screen constitutes a cushion for the bottom sheet of glass and insures a more uniform transfer of heat from the platen to the glass than could otherwise be secured.

Fitting over the set of sheets to be composited is a rubber sheet 22 which is relatively thin as compared to the diaphragm 14. This sheet is very light and may be removed when the cover is raised, but is clamped in position by the cover when the cover is closed, as indicated in Fig. 2. Before lowering the cover to closed position, air is exhausted from the space between the rubber sheet 22 and the platen, the purpose being to withdraw any air which may be entrapped between the opposing surfaces of the pyroxylin plastic sheet 20 and the glass sheets 19, 19. Since the cover 10 of the press is up at this time, the expulsion of the air from between the surfaces of the sheets may be facilitated by the operator who presses down on top of the sheet 22 above the sheets 19, 19, 20 as the air is being exhausted. Since the sheet 22 is relatively thin and light as compared with the diaphragm 14, the tendency of the rubber sheet to press the

edges of the sheets 19, 19, 20 together and prevent the escape of air from the central portions of the sheets, is less than if such sheet were not used and the air were exhausted from beneath 5 the diaphragm. The rubber sheet 22 also protects the diaphragm from cutting on the corners of the upper glass sheet so that when the sheet 22 is used, the diaphragm 14 lasts several times as long as it does when the use of the rubber sheet 22 is omitted. The rubber sheet 22 cuts out where it passes around the corners of 10 the glass sheet, but this sheet, being entirely free from the apparatus when the lid is raised, is easily replaced and its cost is slight as compared 15 with that of the diaphragm 14. The use of the rubber diaphragm, therefore, involves a considerable economy in the operation of the machine. After the air is exhausted from beneath the sheet 22, air pressure is supplied behind the diaphragm 20 14 in order to secure the necessary compositing pressure. This pressure is maintained for several minutes, the sheets to be composited being heated during this period from the platen 1 which is in turn heated by the steam or hot liquid which 25 is circulated through the chamber 2. After the compositing action is completed, the air pressure behind the diaphragm is released, the locking bar 12 is moved back, and the lid is raised, after which the sheet 22 is removed, thus exposing the composited plate which can now be removed. The 30 apparatus is now ready for another compositing action.

In addition to protecting the diaphragm from the sharp edges of the glass and the abrasion of 35 the copper screen, the sheet 22 performs the further function of giving the diaphragm protection from the heat of the platen 1 which protection is another factor tending to increase the life of the diaphragm. The use of the sheet 22 also permits 40 the operator to see after the vacuum is put on whether or not the plates are laid up properly and whether a satisfactory vacuum is applied before the lid is closed. Without this sheet, these conditions would be obscured after the closure 45 of the lid, and the results secured correspondingly less satisfactory.

What I claim is:

150

1. Apparatus for making composite glass comprising a metal platen for supporting the sheets to be composited, means for heating the platen, a movable metal cover fitting over the platen and provided on its inner side with a flexible diaphragm, a flexible sheet impervious to air fitting removably over the sheets to be composited which are supported on the platen, means for exhausting the air from the space between the flexible sheet and the platen with the cover in open position, and means for supplying fluid under pressure behind the diaphragm. 80

2. Apparatus for making composite glass comprising a metal platen for supporting the sheets to be composited, means for heating the platen, a movable metal cover fitting over the platen and provided on its inner side with a rubber diaphragm, a rubber sheet fitting removably over the sheets to be composited which are supported on the platen, means for exhausting the air from the space between the rubber sheet and the platen, with the cover in open position, and means for supplying fluid under pressure behind the diaphragm. 90

3. Apparatus for making composite glass comprising a metal platen for supporting the sheets to be composited, means for heating the platen, a movable metal cover fitting over the platen and provided on its inner side with a rubber diaphragm, a rubber sheet which is relatively thin 100 as compared with the diaphragm fitting removably over the sheets to be composited which are supported on the platen, means for exhausting the air from the space between the rubber sheet and the platen with the cover in open position, and means for supplying fluid under pressure behind the diaphragm. 105

4. A method of making composite glass which comprises superposing a plurality of sheets of glass, interposing a reinforcing material between the sheets which is adapted to be adhesively united thereto, disposing a flat sheet of flexible material impervious to air over one side of the glass, creating a vacuum in the space covered by the material and applying a compacting pressure 115 to the assembly thus formed. 120
